poration of New York

Application April 19, 1945, Serial No. 119,100

Term of patent 14 years

(Cl. D3—26)

To all whom it may concern:

Be it known that I, Jerome Garfinkle, a citizen of the United States and a resident of New York, in the county of Bronx and State of New York, have invented a new, original, and ornamental Design for a Dress, of which the following is a specification, reference being had to the accompanying drawing, forming a part thereof, in which

Figure 1 is a front perspective view of a dress, showing my design;

Figure 2 is a rear perspective view of the same;

Figure 3 is a magnified, fragmentary, sectional view taken on the line 3—3 of Figure 1.

The drawing is shaded for contrast.

The dominant features of the dress include a bias side effect neckline, with cartridge fluting adjacent one shoulder, and with a front plenum and bias stripping, all as shown.

I claim:

The ornamental design for a dress, substantially as shown and described.

JEROME GARFINKLE.
